UNITED STATES PATENT OFFICE.

JACOB J. PLUCKER, OF PHILADELPHIA, PENNSYLVANIA, ASSIGNOR OF ONE-HALF TO
ORMOND RAMBO, OF PHILADELPHIA, PENNSYLVANIA.

HEATER.

1,079,511.

Specification of Letters Patent. Patented Nov. 25, 1913.

Application filed February 11, 1913. Serial No. 747,595.

To all whom it may concern:

Be it known that I, JACOB J. PLUCKER, a citizen of the United States, residing at Philadelphia, in the county of Philadelphia and State of Pennsylvania, have invented certain new and useful Improvements in Heaters, of which the following is a specification.

My invention relates to improvements in heaters, the object of the invention being to provide sectional heaters, either steam, hot water, or hot air with integral air heating passages through which air from the outside is compelled to pass in a long circuitous path and be superheated before discharging into the combustion chamber in close proximity to the fire, so as to consume the otherwise waste products of combustion.

A further object is to provide improvements of this character which form a portion of the furnace as distinguished from an attachment and in assembling the furnace as many of such sections may be utilized as desired.

A further object is to provide a sectional furnace in which several of the sections are formed with integral air superheating passages or chambers with air inlets communicating with the outside, and caps for said inlets to reduce the flow of air.

Heretofore various attachments have been devised for heaters with a view to admitting hot air into the combustion chamber. Such attachments are secured to the furnace in various ways, but due to the heat of the furnace are quickly disabled and are of service but a comparatively short time.

It is the purpose of my invention to provide a furnace section which will have an integral air heating chamber or passage which is a permanent integral part of the section, and not an attachment for the furnace. By reason of this arrangement, the air heater may be cast of the same metal as the sections and of any desired thickness, so that it will be able to withstand the heat of the fire as long as the furnace lasts. My invention is therefore not an attachment but for a permanent part of the heater structure.

With these and other objects in view, the invention consists in certain novel features of construction and combinations and ar-

rangements of parts as will be more fully hereinafter described and pointed out in the claims.

In the accompanying drawings: Figure 1 is a broken view in longitudinal section illustrating my improvements in connection with a sectional hot water heater. Fig. 2 is a view in elevation of one of the sections showing the same at right angles to the position shown in Fig. 1. Fig. 3 is a view in vertical section on an enlarged scale on the line 3—3 of Fig. 2. Fig. 4 is a view in horizontal section on an enlarged scale on the line 4—4 of Fig. 2. Fig. 5 is a view in horizontal section on an enlarged scale on the line 5—5 of Fig. 2. Fig. 6 is a view in section on the line 6—6 of Fig. 3. Fig. 7 is a view in horizontal section illustrating my improvements in connection with a circular heater, and Fig. 8 is a fragmentary view in section on the line 8—8 of Fig. 7.

While my improvements are adapted for use in connection with any style of sectional heater, either for steam, hot water, or hot air, I have illustrated the same in Figs. 1 to 6 inclusive in connection with a sectional hot water heater, and in Fig. 7 in connection with a circular water heater of the sectional type.

Referring to Figs. 1 to 6 inclusive, 1 represents the sections of the heater, and as many of these sections may be secured together as desired. Each section comprises a single integral casting made hollow throughout its upper portion 2, and has legs 3 with a hollow connecting bridge 4 and hollow partition 5, so that passages 6 are formed for the passage of smoke and gases. This particular style of section is not material, as my invention may be used on any style of section, but is shown in connection with this style for purposes of illustration only.

My improved air heating chambers 7 are cast integral with certain of the sections 1, and are preferably spaced from the sections by integral blocks 8, so that the smoke and gases are free to pass all around the air chambers and against practically the entire surface of the section to heat the water. These air chambers 7 in vertical longitudinal dimension are angular in shape, and in transverse horizontal section are oblong in shape.

For clearness of description, I have given the vertical portion of the chamber reference numeral 9 and the horizontal portion 10, but it is to be understood that these are 5 continuous chambers and are divided by a plurality of partitions 11 integral with the walls of the chamber and forming a continuous circuitous passage throughout the chamber. In other words, certain of the 10 partitions 11 extend from the lower end of the chamber to a point short of the end of the horizontal portion 10, while others terminate short of the lower end of the chamber, and extend entirely to the end of the 15 horizontal portion 10.

While I have illustrated but three partitions, it is of course to be understood that the number is not limited, as I may form the passage of any desired length.

20 An integral entrance tube 12 connects the lower end of the chamber 9 at one side with the outside air, and projects slightly beyond the outer face of the furnace section in position to receive a cap 13 to close or partially 25 close the entrance. This cap is designed primarily for use at night when the fire is low, and is preferably attached to the heater by a chain 14 to prevent loss of the cap.

The run of the passage in chamber 7 farthest removed from the entrance 12 is provided in its walls with openings 15, and these openings may be arranged in any desired way to allow the air to escape, and be best distributed over the surface of the 35 fire.

It will be seen that the cold air from the outside entering inlet 12 will be compelled to circulate in a long circuitous passage through the chamber 7, and in such passage 40 will become highly heated by the heat radiation from the walls of said chamber, and when such superheated air finds exit through the perforations 15, it will perfect combustion to a material extent, so that 45 smoke and gases which would otherwise be lost, will be consumed.

As above stated, the chambers 7 are cast integrally with the heater sections. They are not separate attachments, but are formed 50 in the same mold with the sections, and are parts of the sections, and are therefore of the same cast iron and able to withstand the heat to which they are necessarily subjected.

In Figs. 7 and 8, I have illustrated my 55 improvements in connection with a circular heater 16. This circular heater 16 is to be made in sections as all ordinary heaters are to be made, and is provided with an integral air heating chamber 17. This air heating 60 chamber 17 corresponds to the chamber 7 with the exception that it is curved in form,

and at its ends is spaced apart, because they terminate adjacent the furnace door 18.

19 is the air inlet to this chamber 17, and air is admitted to one end of the chamber, 65 and through the medium of the partitions 20, corresponding to partitions 11, the air is compelled to move in a circuitous path throughout the curved chamber 17. The last run of the chamber 17 is provided with 70 perforations 21, so that the superheated air will commingle with the smoke and gases and perfect combustion as in the preferred form. It is to be understood that this chamber 17 is integral with the furnace section, 75 being preferably connected therewith by integral blocks 22 so as to allow a space between the chamber 17 and the wall of the heater for the smoke and gases.

Various other slight changes might be 80 made in the general form and arrangement of parts described without departing from my invention, and hence I do not limit myself to the precise details set forth, but consider myself at liberty to make such changes 85 and alterations as fairly fall within the spirit and scope of the appended claims.

Having thus described my invention, what I claim as new and desire to secure by Letters Patent is:

90 1. A heater comprising a longitudinal series of inverted U-shaped furnace sections, certain of said sections having L-shaped air chambers cast integral with the sections, spaced from the inner walls of the sections 95 and having their horizontal portions located near the tops of the sections, said air chambers having outlets for discharging hot air into the inside of the sections, and having inlets communicating with the outside of the 100 sections, substantially as described.

2. A heater comprising a plurality of sections secured together, certain of said sections having at opposite sides independent air heating chambers, said chambers integral 105 with the section located entirely within the section, having outlets discharging into the inside of the section and inlets communicating with the outside of the section, said chambers of L-shaped form having vertical 110 and horizontal portions, and partitions within the chambers compelling a circuitous passage of air therethrough, substantially as described.

11 In testimony whereof I have signed my name to this specification in the presence of two subscribing witnesses.

JACOB J. PLUCKER.
